BOOKCASE

Robert B. Lindley, San Diego, Calif., assignor to Educational Marketing & Research, Inc., Chicago, Ill., a corporation of Illinois

Filed Mar. 26, 1969, Ser. No. 16,454

Term of patent 7 years

Int. Cl. D6—01

U.S. CL. D33—2

The figure is a perspective view of my new design, in which the view of the side is a mirror image of the opposite side and the view from the front is a mirror image of the back.

I claim:

The ornamental design for a bookcase, as shown and described.
